Primary Examiner — Garth Rademaker*Assistant Examiner* — Fitzgerald L Butac(74) *Attorney, Agent, or Firm* — McCarter & English, LLP(57) **CLAIM**

The ornamental design for a 3D bioprinter, as shown and described.

DESCRIPTION

FIG. 1 is a front view of the 3D bioprinter according to our design;

FIG. 2 is a left side view thereof;

FIG. 3 is a rear view thereof

FIG. 4 is a right side view thereof;

FIG. 5 is a top view thereof

FIG. 6 is a bottom view thereof;

FIG. 7 is a perspective view thereof; and,

FIG. 8 is a enlarged front view of the bioprinter head.

The “dash-dot”broken line seen in FIG. 1 shows the bounds of the enlarged view of a 3D bioprinter head, as seen in FIG. 8, and forms no part of the claimed design.
